UNITED STATES PATENT OFFICE.

OLIVER HAZEN MUNTZ, OF GREENVILLE, PENNSYLVANIA.

DESIGN FOR A HAME-CLIP.

SPECIFICATION forming part of Design No. 18,047, dated February 7, 1888.

Application filed December 17, 1887. Serial No. 258,379. Term of patent 7 years.

To all whom it may concern:

Be it known that I, OLIVER HAZEN MUNTZ, a citizen of the United States, residing at Greenville, in the county of Mercer and State 5 of Pennsylvania, have invented and produced a new and original Design for Hame-Clips; and I do declare the following to be a full, clear, and exact description of the same, reference being had to the accompanying drawings, 10 forming a part thereof.

Figure 1 is a front view of my newly-designed hame-clip. Fig. 2 shows the configuration of the edge of the same.

The leading feature of my design consists in 15 a raised or scalloped blade having outlines somewhat resembling a serrated stiletto-blade, which, when viewed in front, is terminated at its upper end by a narrow hilt-extension having parallel sides and a rounded upper terminus.

A is the center of the blade, which is convex when taken transversely at all points from

the base of the hilt B at *a* to the apex or point at *b*. From the base of the hilt to the point *c* of the guard the configuration is concave, and 25 from the points *c* to the points *d* is a line of beauty forming a swell, *d'*, on each side of the blade, and between the swells *d'* and points *e* and *e'* are concave lines. From the points *e'* to the point of the blade are two cymæ rectæ, 30 forming a contour representing an elongated point of a blade.

I claim—

The design for a hame-clip herein described and shown, the same consisting of a rounded 35 hilt, B, and a blade, A, composed of scallops terminated by a double cymæ point.

In testimony whereof I affix my signature in presence of two witnesses.

OLIVER HAZEN MUNTZ.
